CLAIM

The ornamental design for a combined container mounting apparatus and container.

DESCRIPTION

FIG. 1 is a top, front, right perspective view of a combined container mounting apparatus and container showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, right perspective view of a combined container mounting apparatus and container in an alternate configuration.

The broken lines showing the remainder of the combined container mounting apparatus and container represent unclaimed subject matter and form no part of the claimed design.
